UNITED STATES PATENT OFFICE

RALPH N. ROBERTSON, OF PITTSBURGH, PENNSYLVANIA, ASSIGNOR, BY MESNE ASSIGNMENTS, TO BLAW-KNOX COMPANY, OF BLAWNOX, PENNSYLVANIA, A CORPORATION, OF NEW JERSEY

HANGER

Application filed May 27, 1927. Serial No. 194,836.

This invention relates to means for suspending apparatus, and it relates particularly to hangers for suspending apparatus which are to be installed in boilers or the like. When such apparatus is connected to pipes, or portions of the boiler, such as the steam nozzle, so as to be more or less immovable, it is often difficult to suspend them from fixed points in the boiler, as the hanger will not properly register with the apparatus so as to conveniently make the connection required. Although my invention applies to various other apparatus and uses, yet, for the purpose of this disclosure, I have illustrated and described a steam separator which is mounted in a boiler and which is supported by a hanger.

10

Of the accompanying drawings, Fig. 1 is an end view of a steam separator supported, in a boiler, by hanger which embodies the features of my invention; Fig. 2 is a fractional plan view of the separator and a hanger; Fig. 3 is an enlarged plan view of the hanger alone; Fig. 4 is a side elevation of the hanger; Fig. 5 is an elevation of a modified form of hanger; and Fig. 6 is a side elevation of the same.

In mounting steam separators in boilers it is usually necessary to connect the separator to the steam nozzle of the boiler, and perhaps to drain pipes and the like; so that the separator, in making these connections, becomes substantially fixed in position and can not conveniently be shifted horizontally to register with any fixed suspending means. Even when the separator consists of several sections, some one of the sections is connected to the piping and none of the sections can be conveniently shifted. To obviate the necessity of the points of connection of the separator registering exactly with a certain fixed point of connection to the boiler or the hanger, I provide the means illustrated. These comprise a hanger 10, which is adapted to be slidably connected to the separator 11 and to be fixed, in any suitable manner, to the wall of the boiler 12. The hanger may be arranged to slidably connect with the upper surface of the separator in any suitable manner, such as by means of flanges 13 which

project out and under the elongated flanges, 14. These flanges are fixed to bars 20 which extend as far as may be desired along the upper surface of the separator. I prefer to have these bars extend from one end of each section of the separator to the other, and they may be fixed to the casing by welding or by any suitable means.

The hanger is angularly shaped, having the vertical standard 15, the horizontal arm 16 for connecting to the stud 17, which is fixed to the boiler, and the flange 13, the ends of which project outwardly under the flanges 14. In the arm 16 is an elongated slot 18. The distance between the outer ends of the flange 13 is somewhat less than the distance between the two upright portions of the straps 20, and the ends 21 are rounded somewhat, so that the arm 16 can be turned a material distance to one side or the other in order to properly register with the stud 17.

It will thus be seen that, when the separator section has been fixed in position, it is not necessary for any portion to register with any particular portion of the hanger. The hanger may be shifted along the groove formed by the two straps 20 so far as may be necessary, and the arm 16 can then be turned to one side or the other, if necessary, so that the slot 18 will be in a position to receive the stud 17. This stud can be as long as may be desired and the arm 16 can be supported by means of the nuts 21 at any desired elevation.

In order that the hanger may more rigidly hold the separator section in place, provision may be made for locking it to the separator when the hanger is screwed tightly on to the stud. By making the width of the angular flanges 13 greater than the height of the slot formed by the flanges 14 and the top plate of the separator 11 (Fig. 4), the hanger can be slipped along the slot by tipping the outer end of the arm 16 downwardly, thus tipping the flanges 13 in the slot. Then, when in position, as the nuts 21 are screwed against the hanger, the arm 16 will be forced horizontally, the slot 18 allowing it to move relative to the stud 17. This will bind or lock the flanges 13 in place between the flanges 14 and the separator 11.

It is to be understood that several hangers may be applied to the same section, for instance one at each end of the section, and that modification may be made in the shape of the hanger or the straps 20, without departing from the spirit of my invention.

Fig. 5 shows a modification of a hanger in which the flanges 25 pass inwardly from depending arms 26 on each side of the T-shaped beam 27, which is fixed in any suitable manner to the top of the section. In this case the hanger may be shifted along the T-beam and, by spacing the members 26 apart somewhat more than the width of the top 15 of the beam, the arm 28 can be turned to one side or the other as in case of the hanger of Figs. 1 to 4. And by properly shaping the portions of the hanger and beam which coact, the hanger can be locked in position with 20 reference to the separator section when bolted to the wall of the boiler.

I claim as my invention:

1. Suspending means comprising a pair of spaced parallel straps fixed edgewise to a 25 body to be supported, an elongated flange fixed to the outer edge of each strap and projecting towards the other strap, thus forming a slot with overhanging outer edges, a hanger one end of which is positioned in said slot, said end having flanges extending outwardly under said elongated flanges, the vertical height of said flanges when said hanger extends outwardly in one direction being less than the depth of the slot beneath said elongated flanges, but becoming equal to said depth and binding in said slot when said hanger extends outwardly in another direction.

2. Suspending means as claimed in claim 40 1 in which the other end of said hanger has an angularly projecting arm having a slot therethrough.

3. Suspending means comprising a strap 45 adapted to have one edge fixed to the side of a member to be suspended, an elongated flange projecting angularly from and parallel with but spaced from said side, a hanger adapted to be supported by one end, the other end of said hanger having a flange 50 adapted to be passed between said elongated flange and said side, and being wider than the distance between said elongated flange and the side, whereby said two flanges automatically lock together by pressing against each other when said hanger is tilted to extend substantially at right angles from said elongated flange.

4. Suspending means adapted to suspend 60 one member from another, said means comprising a strap adapted to have one edge fixed to the side of one of said members, an elongated flange projecting angularly from said strap and parallel with but spaced from said side, a hanger adapted to be attached 65 to the other member by one end, and the other

end of the hanger having a flange adapted to be passed between said elongated flange and said side and being wider than the distance between said elongated flange and the side, so that said two flanges lock together by pressing against each other when said hanger extends substantially perpendicular to said elongated flange.

5. A suspending member and a member to be suspended, one of said members having a slot forming means and the other member having a flange adapted to pass into said slot to suspend the member to be suspended, the vertical dimension of said flange when the member is normally suspended being sufficiently greater than the vertical width of said slot to bind said flange in said slot.

6. A suspending member and a member to be suspended as claimed in claim 5, the vertical dimension of the flange, however, being less than the vertical width of the slot when the two members are tilted somewhat from the normal suspending positions.

In testimony whereof, I hereunto set my hand.

RALPH N. ROBERTSON.
